INVENTOR
JESSE C. JOHNSON
BY *First W. Wiegand*
ATTORNEY

UNITED STATES PATENT OFFICE.

JESSE C. JOHNSON, OF OAKLAND, CALIFORNIA, ASSIGNOR TO S. T. JOHNSON CO., OF OAKLAND, CALIFORNIA, A CORPORATION.

ROTARY-OIL-BURNER CONSTRUCTION.

Application filed May 12, 1924. Serial No. 712,685.

To all whom it may concern:

Be it known that I, JESSE C. JOHNSON, a citizen of the United States, residing at 940 Arlington Street, Oakland, in the county of Alameda and State of California, have invented certain new and useful Improvements in Rotary-Oil-Burner Construction, of which the following is a specification.

10 This invention relates to an oil burner and particularly to a burner of the rotary type, in which the oil is atomized and projected by means of centrifugal force.

15 The object of the present invention is, to provide an improvement on the structure shown and described in Letters Patent entitled "Rotary oil burner" granted to me March 11th, 1924, No. 1,486,383.

20 The invention consists of the parts and the construction, combination and arrangements of parts as hereinafter more fully described and claimed, having reference to the accompanying drawings, in which—

25 Figure 1, is a sectional view of the burner atomizing cup equipped with my improvement; and

Figure 2, is a sectional view of the improved burner member.

Referring to the drawings in detail, with- 30 in the rotary atomizing cup 1, a spider mem- ber 2 is secured, and the cup is rotated by a motor through the propelling shaft 3. The outer end of this shaft is reduced as at 4, upon which the spider member is se- 35 cured by means of a securing bolt 5, ex- tending inwardly axially of the shaft, the said bolt terminating in a head 6, whereby the bolt may be properly positioned. The inner edge of the cup being extended in- 40 wardly to form an annular flange 7. Se- cured within the burner casing 8, is an an- nular sleeve 9, surrounding the propelling shaft 3 and extending into the atomizing cup 1, thus forming the inner wall of an oil supply conduit.

45 The present improvement consists par- ticularly in the construction of the outer

wall member of said oil supply conduit. It is constructed substantially as shown in Fig. 2.

This outer wall member 10, secured to a part of the burner casing 8, preferably threaded therein as at 11, is, at the inner end thereof provided with a frusto-conical shaped bore having its widest opening at 55 the inner end 12 thereof, said opening re- 60 ducing in diameter as it approaches and enters the atomizing cup, as shown at 13, thus forming with the sleeve 9, a conical chamber 14, into which the fuel oil is delivered un- 65 der a constant pressure from a pumping system by means of a conduit 15.

The outer end of this wall member is provided with a cylindrical bore 16, of a sufficient size to surround the atomizing cup 65 1 in a spaced relation, said bore 16 being provided at its base, with a recess 17 to form an annular channel for the annular flange 7 of the atomizing cup 1 and in a spaced relation thereto.

70 The outer edge 18 of this wall member approaches in close proximity, the outer edge of the atomizing cup.

In operation, oil is fed into the chamber 75 14 through the pipe 15 by means of a pump- ing system under a constant pressure, to be delivered to the atomizing cup and any leakage or drip of oil, not consumed by the revolving atomizer, forcing its way back- 80 ward at the annular flange 7 of the atomiz- 85 ing cup, will, by reason of the construction of this outer wall member, be carried for- ward into the furnace and prevented from accumulating within the burner casing.

Having thus described my invention, what I claim and desire to secure by Letters Patent is—

In combination with a propelling shaft and an atomizing cup, an inwardly extend- 90 ing annular flange on said cup, an element provided with a frusto-conical bore at its inner end, and at its opposite end provided with a cylindrical bore of sufficient size to surround said atomizing cup in a spaced

relation, an annular sleeve surrounding said propelling shaft, said sleeve extending into said atomizing cup and forming with the said frusto-conical bored part of said element, an oil feed conduit for said atomizing cup, an annular recess provided in the cylindrical bored part of said element said recess being in a spaced relation to said annular cup flange, whereby any leakage or

drip of oil from said oil feed conduit at 10 the cup flange will be utilized.

In testimony whereof I have affixed my signature in the presence of two witnesses.

JESSE C. JOHNSON.
